BOTTLE CAP

Morgan C. Atwood, New Orleans, La.

Application March 22, 1938, Serial No. 197,486

1 Claim. (Cl. 215—46)

This invention relates to bottle caps of the type having a disc top, a corrugated flared skirt adapted to be crimped over the bead or swell in a bottle neck, and a sealing disc adapted to seal the neck of the bottle gas tight.

Caps of this type are opened with a bottle opener and it has been proposed to equip the caps with tearing tabs for eliminating the use of the bottle opener. In all proposed types of tearing tabs the tabs extend downwardly from the bottom of the skirt and over the swell or bead in the neck of the bottle. Such tearing tabs have not come into general use, one reason being that in practically all bottling plants bottles must be handled at least once by hand from the conveyor to the cases, after the bottles are capped. There is a standard way of handling these bottles, that is, by grasping three bottles by the necks, between the fingers of each hand. Tearing tabs that project downward from the caps are found to injure the hands of the workmen seriously at the rate of speed they are compelled to work.

With this disadvantage in mind, an object of the present invention is to provide a cap of this type having a turned up rolled edge on one side extending outward slightly beyond the swell or bead in the neck of the bottle and adapted to be pushed up by the operator's thumb without injury to the thumb, thus eliminating in practice any injury to workmen's hands in handling the capped bottles.

In conventional caps of this type, to promote easy removal without the use of a bottle opener, it has been proposed to provide open slots in the skirt to weaken the cap so that the tearing tab can be effectively used. These slots permit gas escaping with consequent spoiling of the contents of the bottle.

With this disadvantage in mind the present invention creases or scores the skirt at the ends of the rolled up edge of the cap, to sufficiently weaken the cap, while small V-notches are made at the bottom of the crease, extending about one-third of the way up the skirt of the cap. These V-notches make it very easy to push up the rolled edge extending around one-half the periphery of the skirt and break the cap along the scores and across the disc top to effect easy removal.

Hitherto tearing tabs or tangs have been comparatively narrow and when pulled up, in practice, simply tear a narrow strip through the top leaving more than half of the cap on the bottle with two sharp ragged edges to injure the operator's fingers when further effort is made to remove the cap. With this disadvantage

in mind the present invention provides a rolled up edge extending from two diametrically opposite scores or V-notches in the skirt and gradually increasing in diameter from nothing at said notches to the center so that when thumb pressure is applied half of the cap must be forced up to an angle of about 45 degrees and when this is accomplished the cap will drop off the bottle neck without manual attention.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification:

Figure 1 is a side elevation of a bottle cap constructed in accordance with the invention, applied to a bottle.

Figure 2 is a bottom plan view of the bottle cap shown in Figure 1.

Figure 3 is a cross sectional view of the bottle cap taken on the line 3—3 of Figure 2 and showing the cap in applied position.

Figure 4 is a detail cross sectional view taken on the line 4—4 of Figure 2 and showing the diameter of the rolled up edge near its maximum contour.

Figure 5 is a detail cross sectional view taken on the line 5—5 of Figure 2 showing the diameter of the rolled up edge near one of its ends.

Figure 6 is a detail cross sectional view taken on the line 6—6 of Figure 2 and showing one of the V-notches and scores.

Figure 7 is a side elevation of the cap in the operation of being removed from the bottle neck by thumb pressure.

Figure 8 is a detail sectional view showing score lines formed at opposite points on the inner face of the cap flange for weakening the flange to promote easy removal.

Referring now to the drawing in which like characters of reference designate similar parts in the various views, the reference numeral 10 designates a bottle having the neck terminating in a conventional swell or bead 11. In carrying out the invention a bottle cap is provided, having a disc top 12, a corrugated flared skirt 13, adapted to be crimped over the bead 11 of the bottle neck, and a sealing disc 14 confined against the bottom face of the disc top 12 and adapted to seal the bottle liquid and gas tight.

The wall of the skirt is provided with creases or scores 16 at diametrically opposite points, and an inverted V-notch 18 is formed at the bottom of the score and extends about one-third the way up the skirt of the cap.

The edge of the skirt between the V-notches is provided with excess material which is rolled back upon itself to provide a thumb rest 17 which gradually increases in diameter from its V-notches to the center. The rolled up edge extends out slightly beyond the swell or bead of the bottle neck as best shown in Figure 3.

In operation the operator places his thumb against the rolled up edge 17 and pushes the same upwardly, this thumb pressure forcing one-half of the cap upwardly to an angle of about 45 degrees, as best shown in Figure 7, the V-notches and scores readily tearing during the initial part of the operation while continued thumb pressure forces the cap to drop off the bottle neck. The rounded or rolled contour of the thumb rest 17 prevents injury to the operator's thumb while pressure is being applied and it is found, in practice, that bottles capped with caps of this type can be handled by workmen expeditiously and without injury to the hands when transferring the same from the conveyor to the cases.

From the above description it is thought that the construction and operation of the invention will be fully understood without further explanation.

What is claimed is:

A bottle cap including a disc top, a corrugated skirt adapted to be crimped over the bead of a bottle neck, a sealing disc confined against the bottom face of the disc top, there being tearing scores formed at diametrically opposite points in the skirt and extending from the edge of the skirt upwardly approximately to the sealing disc, and a rolled up edge portion formed on one side only of the skirt and adapted to extend outwardly beyond the bead of the bottle neck, said rolled up edge portion increasing in width from nothing at said scores to about a maximum of twice the depth of the corrugations in the skirt at the center of the rolled up edge portion, said rolled up edge portion forming a crescent shaped grip adapted to be manually grasped and pulled upward for severing the skirt at the scores to dislodge the cap from a bottle neck.
